(57) **CLAIM**

The ornamental design for a cap, as shown and described.

DESCRIPTION

FIG. 1 is a top view of a cap showing my new design;
FIG. 2 is a bottom view of the cap;

FIG. 3 is a front view of the cap;

FIG. 4 is a rear view of the cap;

FIG. 5 is a right side view of the cap;

FIG. 6 is a left side view of the cap; and,

FIG. 7 is a top front side perspective view of the cap.

The long-dashed broken lines define portions of the cap that form no part of the claimed design. The short-dashed broken lines depict claimed stitching of the cap.
The various densities of the applied stippling techniques along the surfaces of the cap represent a contrast in appearance and do not illustrate a particular material, surface ornamentation, or surface decoration.**1 Claim, 6 Drawing Sheets**FIG. 1
